CLAIM

The ornamental design for a suspension lamp, as shown and described.

DESCRIPTION

1.1 is a front perspective view of a suspension lamp, showing my new design;

1.2 is a front view;

1.3 is a rear view;

1.4 is a bottom view;

1.5 is an atop view;

1.6 is an right side view; and

1.7 is a left side view.

The suspension cable for the suspension lamp is shown with a symbolic break in length.

The appearance of any portion of the cable between the break lines forms no part of the claimed design.
